UNITED STATES PATENT OFFICE.

JOHN G. UTZ, OF DETROIT, MICHIGAN, ASSIGNOR TO CHALMERS-DETROIT MOTOR COMPANY, OF DETROIT, MICHIGAN, A CORPORATION OF MICHIGAN.

INDUCTION-CONDUIT FOR EXPLOSION-ENGINES.

968,002.

Specification of Letters Patent. Patented Aug. 23, 1910.

Application filed December 5, 1908. Serial No. 463,157.

To all whom it may concern:

Be it known that I, JOHN G. UTZ, a citizen of the United States of America, residing at Detroit, in the county of Wayne and State of Michigan, have invented certain new and useful Improvements in Induction-Conduits for Explosion-Engines, of which the following is a specification, reference being had therein to the accompanying drawings.

10 The invention relates to explosion engines and more particularly to the means employed for introducing the carbureted air into the explosion chamber.

15 The invention consists in the construction by which the mixture is warmed during its passage from the carbureter to the engine cylinder, as hereinafter set forth.

20 In the drawings—Figure 1 is a side elevation of an explosion motor to which my improvements are applied; Fig. 2 is an elevation at right angles to Fig. 1.

25 In the operation of explosion engines in which liquid fuel is employed it has been found desirable to warm the carbureted mixture before introduction into the explosion chamber. The present invention accomplishes this result by extending the induction passage along the wall of the water jacket for the engine cylinder whereby it will be 30 substantially heated by the water within the jacket. As shown, A is a multi-cylinder explosion engine, and B is the water jacket surrounding the cylinders.

35 C is a removable plate forming a portion of the wall of the water jacket and through which access may be obtained to the interior, said plate being secured by suitable means, such as the tap screws D.

40 E are the induction ports, two of these being shown, for feeding the several cylinders.

45 The induction conduit which connects with the ports E is preferably cast integral with the plate C, and, as shown, is of a Y-shaped form. The stem F of the Y extends outward and downward from the plate C and is adapted for direct attachment to the carbureter, while the branches G and G' of

the Y lie adjacent to the plane of the plate C and receive heat directly therefrom by conduction. At their upper ends these branches G and G' extend beyond the upper edge of the plate C and are provided with flange bearings H for coupling them to the engine casing and in registration with the ports E.

50 It will be apparent that the induction conduit, and particularly the portions G and G' thereof, will constantly receive heat from the water in the jacket, and will be maintained at substantially the same temperature. Thus the carbureted mixture passing through the conduit will be warmed before entrance to the cylinders.

55 What I claim as my invention is:

1. The combination with an explosion engine provided with a water jacket, of a removable plate forming a portion of the wall of said jacket, and an induction conduit formed integral with and extending along the exterior of said plate and having its opposite ends communicating respectively with the carbureter and the inlet for the engine.

60 2. The combination with an explosion engine provided with a water jacket, of a removable plate forming a portion of the wall of said jacket, an induction conduit formed integral with and extending along the exterior of said plate, the opposite ends of said conduit projecting beyond the removable plate and communicating with the carbureter and the engine inlet.

65 3. The combination with an explosion engine having a plurality of cylinders, of a water jacket therefor, a removable plate forming a portion of the wall of said jacket, and a Y-shaped induction conduit for the carbureted mixture extending along the exterior of said plate and having the ends of the branches of the Y projecting therebeyond and communicating with the cylinder inlet and having the stem of the Y extending beyond the plate and communicating with the carbureter.

70 4. The combination with an explosion engine, of a water jacket therefor, a remov-

able plate forming a portion of the wall of
said jacket, a Y-shaped induction conduit
for the carbureted mixture formed integral
with and extending along the exterior of
5 said plate and having the ends of the
branches of the Y projecting beyond the
plate and connected with the inlets of the
cylinder and having the stem of the Y ex-

tending beyond said plate and communicat-
ing with the carbureter.

In testimony whereof I affix my signature
in presence of two witnesses.

JOHN G. UTZ.
